UNITED STATES PATENT OFFICE

OTTO EUGENE HUBER, OF READING, PENNSYLVANIA, ASSIGNOR TO THE NARROW FABRIC CO., OF WEST READING, PENNSYLVANIA, A CORPORATION OF PENNSYLVANIA

DESIGN FOR A LACE BRAID

Application filed March 10, 1930. Serial No. 34,805. Term of patent 14 years.

To all whom it may concern:

Be it known that I, OTTO EUGENE HUBER, a citizen of the United States, residing at Reading, in the county of Berks and State of Pennsylvania, have invented an original and ornamental Design for Lace Braid, of which the following is a specification, reference being had to the accompanying drawing, forming part thereof.

The drawing is a plan view of a lace braid embodying my ornamental design.

I claim:

The ornamental design for a lace braid, as shown.

In testimony whereof I affix my signature.

OTTO EUGENE HUBER.
